FEED MECHANISM FOR MATCH-PACKING MACHINES.

1,206,823.

Specification of Letters Patent.

Patented Dec. 5, 1916.

Application filed April 28, 1914. Serial No. 834,905.

To all whom it may concern:

Be it known that I, JOSEPH C. DONNELLY, a citizen of the United States, and resident of Barberton, in the county of Summit and State of Ohio, have invented certain new and useful Improvements in Feed Mechanism for Match-Packing Machines, of which the following is a specification.

This invention relates to feed mechanism for match packing machines, having reference more especially to means whereby matches, as rapidly as they are discharged from a match making machine, are intercepted and thence conveyed in an orderly manner to a box filling station or stations.

In the form of embodiment of my invention herein illustrated the feed mechanism is associated with a match packing machine of the character set out in Letters Patent of the United States No. 1,016,436, dated February 6, 1912. In the said patented machine the matches are delivered to the upper or receiving end of an inclined hopper or trough having in the bottom of its lower or discharge end two suitably-located measuring chambers to which the matches are progressively fed by longitudinal vibration of the trough. Box trays to be filled with matches are impelled by an intermittently movable endless carrier along two parallel paths extending beneath the respective measuring chambers of the trough, and provisions are had whereby the bottoms of the chambers are opened and closed at predetermined intervals in respect to the intermittent travel of the train of trays, in order that the contents of such chambers shall be deposited into the trays underlying the same, each tray being periodically supplied with quantities of matches from the respective chambers. Among other things, provisions are had whereby the box trays are raised and lowered at intervals in respect to the measuring chambers in order to insure the orderly transference of the matches to the trays, all as will more fully appear by reference to said Letters Patent.

My invention comprises, primarily, a trough or hopper having therein a longitudinally-reciprocating bottom member and relatively fixed stop devices adjacent thereto, said member being constructed and arranged to engage the opposing matches

within and progressively advance them along the trough, and said stop devices being disposed in the path of the matches so as to act not only to straighten or parallelize them across the trough but also to prevent their retrograde motion in the back strokes of said member.

My invention also comprises means whereby the matches are positively fed along the space in the vicinity of and between the measuring chambers of the trough.

My invention also comprises means whereby is attained an efficient jarring of the mass of matches banked at the discharge end of the trough, in order to cause them to settle down into the measuring chambers and also to pass freely from said chambers to the underlying box trays when the bottoms of the chambers are opened to said trays.

My invention also comprises a reciprocating yielding pressure structure which is constructed and arranged to act upon the mass of matches within the trough and contribute to their orderly advancement along the same.

My invention also comprises various novel features of construction and operation, which will be hereinafter described and claimed.

In the drawings—Figure 1 is a plan view of match feeding mechanism embodying my invention, only so much of the match making and packing machines being shown as is necessary to illustrate the relation of the said mechanism thereto. Fig. 2 is a front elevation of Fig. 1. Fig. 3 is an elevation, partly in section, of the portion of the feed-trough, and adjuncts, adjacent the match machine. Fig. 4 is a horizontal section, as on the line 4—4 of Fig. 3. Fig. 5 is a plan of the portion of the feed-trough, and adjuncts, adjacent the packing machine. Fig. 6 is a side elevation of the mechanism shown in Fig. 5. Fig. 7 is a perspective view of a reciprocating pressure structure which is designed to act upon the matches within the feed-trough. Fig. 8 is a longitudinal vertical section through the discharging end of the feed-trough and adjuncts. Fig. 9 is a perspective view of a vibrating rack frame which is located within the trough in the space between the discharge openings.

Fig. 10 is a transverse vertical section through the feed-trough and adjuncts on a plane through the match carrier of the match making machine, as on the line 10—10 of Fig. 3. Fig. 11 is a similar section through the feed-trough, as on the line 11—11 of Fig. 6. Figs. 12 and 13 are transverse sections, as on the lines 12—12 and 13—13, respectively of Fig. 6.

16 20 designates a portion of the match carrier of a match making machine, from which carrier the matches are ejected row by row in the usual manner.

21 designates a trough which is arranged 15 in front of the carrier in a position to receive the matches in parallelism, or substantially so, as rapidly as they are ejected and convey them thence to the box-trays. In the present instance the trough declines 20 partially from its receiving end toward its discharging end, terminating thereat in a substantially horizontal portion in which are provided in spaced relation to each other the discharge openings 22, 23 for the 25 matches. These openings are positioned above the respective parallel paths of the intermittently movable tray-carrier 24 of the filling machine and are adapted to deliver measured quantities of matches to the 30 trays 25 which are borne by the successive links of the carrier. The openings are associated with depending walls which, in conjunction with the side walls of the trough, constitute measuring chambers for 35 the matches. Each of these chambers is equipped with sliding gates 26, 26' by actuation of which the bottom of the chamber may be opened and closed at predetermined 40 intervals in relation to the intermittent feed of the match trays to be filled, as will hereinafter appear.

The trough in its preferred construction includes two parallel side walls 27 adequately separated, as by bottom cross-pieces 45 29, to afford an interior space slightly greater in width than the length of a match. At the lower portion of the trough is an end wall 28 which is vertically slotted as at 28' for a purpose hereinafter appearing. The 50 body of the trough is connected with and supported by a suitable frame structure 30 which may be bolted to an adjacent portion of the frame of the match making machine. In the present instance the body is provided 55 at its upper end with depending lugs 31 which are pivotally connected to a bracket 32 on the structure 30 so that such body may be bodily swung up or down to a limited extent in order to adjust its lower discharge 60 portion vertically in respect to the portion of the filling machine adjacent thereto. Pivoted to the body of the trough is a depending slotted arm 33 through the slot of 65 which extends a bolt 34 from a bracket 35 on the supporting structure, so that by prop-

erly turning the nut of the bolt the said arm may be released to permit vertical adjustment of the trough and may then be clamped to lock the trough in its position of adjustment.

The portion of the rearward wall of the trough directly in front of the match carrier is omitted, and in lieu thereof a plate 35' is bolted to the frame of the match machine, the upper edge of which plate is 75 in a horizontal plane immediately below the plane of discharge of the matches from the match carrier. Thus the vertical adjustment of the body of the trough does not affect the position of the upper edge of the 80 plate relative to the plane of discharge. Such edge is located near the bottom of the trough so as to obviate liability of the matches becoming awry during their descent. (See Fig. 10.)

The bottom of the trough is constituted in the main by two longitudinally vibrating match feeding sections of special construction, marked 36 and 37 respectively. The main section 36 extends from the upper or 85 right hand end of the trough adjacent the corresponding edge of the match carrier, to a point adjacent the inner discharge opening; and the other or auxiliary section 37 is located in the space between the two 90 openings. (See Fig. 8.)

The main feeding section 36 is loosely supported on or adjacent the bottom pieces 29 of the trough being provided on its under side with inclined guide arms 38 which are slidingly fitted to correspondingly inclined guide-extensions 39 on two of the bottom pieces, whereby longitudinal reciprocation of the section, as hereinafter described, effects a rising and falling feed 100 movement thereof, that is to say, the section 36 is raised on its forward stroke toward the discharge openings of the trough and then is lowered on its rearward or return stroke. The top of this feeding section 36 105 is provided with transverse step-like portions 40, which constitute, in effect, rack teeth, and the adjacent sides of the trough are provided on their inner walls throughout the length of the section with stop-members 41 comprising ledges provided with similar step-like portions 42. The bottom of the trough, in the space between its receiving end and the inner discharge opening, thus includes two lateral series of fixed 110 steps or teeth 42 and an intermediate series of vibratory steps or teeth 40. Hence when the matches are delivered row by row from the match machine to the receiving end of the trough the steps of the vibrating bottom section in its uprising forward stroke 115 act to engage the sides of the lowermost matches and feed them progressively along the trough to the discharge openings, and the adjacent fixed teeth, in the falling rear-

ward stroke of said section, serve as stops to engage the matches near their ends and prevent retrograde movement thereof. Thus the matches are maintained in parallelism within the trough. It is to be noted that the steps of the feeding section do not lift the matches above the fixed steps on which the matches are supported, but simply move to position in rear of the bodies of the opposing matches and push them with a direct thrust along the trough. This feature of coördinated feeding and stop teeth is an important one, as thereby is provided a simple and reliable means whereby the matches are not only positively fed along the trough but are kept well under control during their travel.

It is to be noted that the trough is inclined on account of the different elevations 20 of the discharging and filling stations of the types of match and packing machines respectively herein illustrated; and that the rising and falling motion is imparted to the inclined section 36 in order to compensate 25 for the inclination of its rack-teeth. Where, however, such stations are on the same level, or nearly so, a trough with a horizontally-mounted step-section for feeding the matches may be used, in which case the latter may 30 be given a direct horizontal instead of a rising and falling motion. It is also to be noted that the toothed members 41 instead of being fixed, as above described, may be reciprocated in alternation with the central 35 section 36 the juxtaposed teeth thus coöperating to feed the matches and maintain them in parallelism.

In the present instance the feeding section 36 is longitudinally vibrated through a link connection 43 with a crank wheel 44 on a short shaft 45 having its bearings in brackets 46 on the frame structure 30. Fast on this shaft is a friction wheel 47 with the face of which contacts a friction driving 45 wheel 48 on a shaft 49 which has its bearings in brackets 50 also on said structure. The shaft 49 is provided with a sprocket wheel 51 which is connected by a chain 52 with a driving sprocket wheel (not shown). 50 The shaft 49 is slidingly mounted in its bearings so that it may be manually shifted to move the friction wheel 48 into or out of operative contact with the face of the wheel 47. It is obvious that by moving the contacting wheel 48 more or less toward the center of the wheel 47, the speed of the latter, and consequently the rate of vibration of the feeding section, may be varied. In 55 the present instance the shaft 49 is pivotally coupled, as at 53, to a rod 54 which extends through suitably-disposed bearing brackets 54' on the frame of the filling machine to a point in front of the latter terminating in a suitable operating handle 55. (See Fig. 2.) 60 Any other appropriate means for actuating

the toothed feeding section may be employed.

The auxiliary section 37, which is stepped or toothed as indicated at 56 similarly to the section 36, rests upon the inclined top of a 70 standard 57 on the bed 58 of the filling machine. The section 37 is provided with a depending lug having a laterally projecting shaft 59 which is pivotally connected by means of a link 59' with the section 36, 75 and thus the two sections are simultaneously reciprocated longitudinally of the trough. The inclination of the supporting surface of the standard 57 is such that an upward forward movement and a downward return 80 movement are imparted to the reciprocating section 37, and thus, (similarly to the corresponding motion of the section 36,) is effected a forward feeding of the superposed matches from the inner to the outer discharge opening of the trough.

The auxiliary section 37 is fitted to slide between the spaced longitudinal side members 60 of a vibrating frame within the lower part of the trough, said members being provided on their upper edges with inclined teeth 61 corresponding with those 56 of said section, which teeth 61, similarly to the fixed lateral teeth 42 previously described, are constructed and arranged to engage the opposing matches and prevent their retrograde movement during the return strokes of the adjacent feed section 37. This frame is provided with lateral flanges 63 which extend beneath the adjacent walls of 100 the trough and bear cap-plates 64 which afford longitudinal guide-ways to receive corresponding gibs 65 on the exterior of said walls. The flanges 63 are longitudinally and vertically extended at the respective ends of the side members 60, as at 65', so as to embrace the trough, the extensions at the outer end of the frame being connected by a wall 66 which is slotted, as at 66' to afford clearance for the respective sides of the trough. 110 The ends of the members 60 adjacent the wall 66 are provided with a depending wall 67, such walls being in spaced relation to each other to afford, in conjunction with the proximate side walls of the trough, a rectangular measuring chamber directly beneath the outer discharge opening 22 of the trough. The opposite ends of the members 60 are provided with a depending cross wall 68 which is spaced from a similar wall 69 on the adjacent bottom piece 29 of the trough; such walls 68, 69, in conjunction with the intervening side walls of the trough, providing a measuring chamber beneath the inner discharge opening 23 of the trough.

The depending walls 67 and 68 of the respective measuring chambers preferably comprise the vertical members of separate angular plates the upper members of which are fitted to slots in the ends of the toothed

members 60 and secured therein by screws 70 so as to be adjustable toward and from the opposite walls of the respective chambers.

The depending wall 69 is preferably formed by the vertical member of an angular plate which is slidably mounted in the adjacent bottom piece 29 for adjustment toward and from the opposite wall 68 in order to vary the capacity of the measuring chamber as occasion may require. Preferably the horizontal member of the plate is provided with a depending lug 70' having a tapped orifice with which is engaged a setscrew 71 rotatably mounted in a lug 72 on the adjacent bottom piece of the trough, so that by properly turning the screw nice adjustment of the angle plate may be had. (See Figs. 8 and 9.)

The frame is given a short vibratory motion in order to jar the matches at the lower end of the trough and cause them to settle compactly within the respective measuring chambers, the walls of said chambers by their vibration also insuring the discharge of the matches to the underlying box-trays when the bottoms of the chambers are opened, as hereinafter described.

In the present instance a pneumatic vibrator 73 for the frame is employed, the piston 20 ton of said vibrator being connected to an arm 74 on a vertical rock-shaft 75 having its bearings in vertically-spaced brackets 76 on the standard 57. An arm 77 on the upper end of this shaft is pivotally connected to a bar 78 which is attached at its ends to pins 79 fast on laterally projecting brackets 80 on the respective end portions of the frame. By regulating the volume of air supplied to the vibrator cylinder, the rapidity of the 30 jarring action of the frame can be nicely adjusted as occasion may require. (See Figs. 5 and 6.) In the present instance also each of the measuring chambers is provided with two gates 26, 26', which are movable toward and from the median portion of the chamber. The outer gate 26 of each chamber is affixed to a slide 81 which is fitted to a guide-way in a reciprocating cam-actuated head 82. This head is slidably fitted to ways in a bracket 83 on the frame of the filling machine, and is coupled by means of a link 84 to a rock lever 85 which is connected with and timely actuated by a cam (not shown) of the filling machine as set out in Patent No. 1,016,436 aforesaid. The slide 81 is recessed on its under side for the reception of a retracting spring 86 one end of which bears against the slide and the other end against a pin 87 on the head. Thus the gate 26 has capacity for 40 independent yielding movement as it is moved into the measuring chamber, and in consequence any liability of crushing or jamming opposing misplaced matches which may be sticking up in the underlying box tray is obviated. (See Fig. 8.) Each of the

gates 26 is connected at its outer end by means of a laterally-extending plate 88 with a slide-block 89 which is loosely fitted on the shifting rod 54.

The inner gate 26' of each of the measuring chambers is bifurcated to embrace the adjacent portion of the standard 57, one of the limbs of the gate being slidably supported on a lateral extension of the standard by a screw and slot connection 90. (Figs. 8, 12 and 13.) The other limb of the gate 26' is attached to one (91) of the parts of a two-part slide-block which is loosely fitted on the rod 54. The parts 91, 91' of the block are connected by a retracting spring 93 so as to have capacity for yielding longitudinal movement relative to each other, on the rod 54. The part 91' of the slide-block for the gate 26' of one chamber is rigidly connected by means of a rod 92 with the cam-actuated slide-block 89 for the outer gate 26 of the other chamber. Hence both gates of each chamber are actuated simultaneously, either to open or to close the chamber; the respective gates 26', by virtue of the spring 96 connection of the block parts 91, 91' having capacity for independent yielding movement, similarly to the gates 26, as said gates 26' are being moved into closing position.

Preferably the teeth of the ledges 41, of the match feeding sections 36, 37 and of the vibratory frame structure, respectively are slightly inclined downwardly from the inner to the outer side of the trough, as shown most clearly in Figs. 10 to 13, inclusive, so as to compensate for the headed ends of the matches and insure a substantial level of the contained mass along the trough when the trough is well supplied with matches.

In order to avoid any liability of the matches piling above and overflowing the sides of the trough, I preferably provide a special feeding structure which is constructed and arranged to bear yieldingly upon the contained matches and assist them in their travel along the trough. This structure is clearly shown in Figs. 1, 2, 5, 6 and 7. It includes a rod 94 which extends longitudinally of the trough, in the left-hand portion of the latter, the lower edge of the rod being preferably serrated or toothed as at 95, to engage the mass of underlying matches and its outer extremity being bent upwardly, as at 96, to provide a convenient handle portion to facilitate the manual raising of the rod if desired. The opposite end of this rod is pivoted to an eccentric or crank disk 97 on a stud shaft 98 which has its bearing in a bracket 99 on one side of the trough. This shaft bears a pulley 100 which is connected by means of a belt 101 with a suitable driving pulley (not shown). Thus the rod 94 is longitudinally reciprocated. Secured to the said rod at intervals, are overlapping looped wire-frames 102 the free ends of which de-

pend below the rod so as to act as yielding feed-pawls upon the opposing mass of matches during the forward stroke of the rod, and thus grasp and hold down substantial quantities of matches and assist in feeding them toward the discharge portion of the trough. An additional looped wire frame 103 is secured to the rod, so as to extend through the vertical slots 28' in the end 5 wall of the trough, and thus yieldingly bear upon the underlying matches in the vicinity of the measuring chambers. To lift the rod and its spring feed-pawls 102 above the matches, during the back stroke of the rod, 10 and thus avoid disturbance of the matches, the rod is provided near its outer end with an upright bracket 104 bearing an anti-friction roller 105 which rests upon one arm of a rock-lever 106 which has a pivotal pin- 15 slot connection 107 with a bracket 108 on one side of the trough. The other arm of the lever is eccentrically connected, as at 20 109, with the pulley 100, and is thereby longitudinally reciprocated and vertically os- 25 cillated; the respective crank connections for the rod and lever being so positioned relative to each other that the free arm of the lever is lowered during the forward stroke of the feed-rod 94 and is raised during 30 the rearward stroke of the latter.

As described in Patent No. 1,016,436 aforesaid, the box trays are raised and lowered when they are beneath and in the vicinity of the measuring chambers, the contents 35 of the trays as the latter leave the respective chambers being subjected to the action of suitable leveling or distributing plates 110, 111, respectively. In the present instance the plate 110 is slidably supported, 40 so as to be vertically movable, on a bracket 112 which is affixed to an adjacent end extension of the vibrating frame, and the plate 111 is secured to a bracket 113 which is af- 45 fixed to an adjacent extension at the opposite end of said frame.

By the above-described mechanism it will be seen that the matches are punched directly from the match machine into the trough and that the receiving end of the 50 trough may be kept supplied with matches to or near to the horizontal plane of the ejecting punches. This insures an orderly disposition of the matches within the trough at the outset, which is the critical period. 55 The matches thus deposited in the trough are not only positively fed along the trough with an easy motion to the filling stations but they are kept straight during their entire travel, and this whether the trough be in 60 a horizontal plane or inclined thereto.

It is to be understood that my invention is not limited to the specific structural features shown and described, as the same may be modified without departure from the 65 principle of the invention.

What I claim is—

1. In match-feeding mechanism, an elongated trough to one end of which the matches are delivered in mass, said trough comprising a body, a vibratory bottom section therefor having transverse rack teeth or projections arranged to engage the lowermost matches and progressively feed them with a direct thrust longitudinally of the trough, and stop devices adjacent said section to engage the matches and prevent their retrograde movement during the operation of said section. 70

2. In match-feeding mechanism, an elongated trough to one end of which the matches are delivered in mass, said trough comprising a body and juxtaposed longitudinal bottom members having rack teeth transversely thereof, in combination with means for effecting longitudinal movement 80 of said members relatively to each other and progressively impelling the lowermost matches with a direct thrust longitudinally of the trough. 85

3. In match-feeding mechanism, an elongated trough to one end of which the matches are delivered in mass, said trough comprising a body and juxtaposed longitudinal bottom members having rack teeth transversely thereof, one of said members being longitudinally movable, and the others stationary, in combination with means for vibrating said movable member whereby its teeth engage the lowermost 90 matches and progressively impel them with a direct thrust longitudinally of the trough. 95

4. In match-feeding mechanism, an elongated trough to one end of which the matches are delivered in mass, said trough comprising a body and juxtaposed longitudinal bottom members having rack teeth transversely thereof, two of said members being stationary and the middle member being longitudinally movable, in combination with means for vibrating said movable member whereby its teeth engage the lowermost matches and progressively impel them with a direct thrust longitudinally of the trough. 100

5. In mechanism of the character described, a match-feeding trough arranged alongside of the discharge end of a match machine, and into which the matches are discharged in rows directly from the match machine, a longitudinally reciprocating bottom section for said trough, having on its upper surface transverse rack teeth arranged to engage the lowermost matches and progressively feed them with a direct thrust longitudinally of the trough, means 110 for vibrating said section, and stop devices within the trough and adjacent said section to prevent retrograde movement of the matches during the operation of said bottom section. 115

120

125

130

6. In mechanism of the character described, a match-feeding trough arranged alongside of the discharge end of a match machine, and to which the matches are discharged in rows directly from the match machine and extending thence away from the match machine, and having discharge openings in the bottom of such extended portion, a longitudinally reciprocating bottom section for said trough having on its upper surface transverse rack teeth arranged to engage the lowermost matches and progressively feed them with a direct thrust longitudinally of the trough, means 10 for vibrating said bottom section, stop devices within the trough and adjacent said section to prevent retrograde movement of the matches during the operation of said bottom section, and means for feeding box 20 trays beneath said extension to receive the matches from the respective openings.

7. In match-feeding mechanism, an elongated trough to one end of which the matches are delivered in mass, said trough comprising a body, a vibratory bottom section for said body having transverse rack teeth or projections, means for longitudinally vibrating said section and imparting thereto rising and falling motions during 30 its forward and return strokes respectively, whereby the said teeth or projections are caused to engage the lowermost matches and feed them with a direct thrust longitudinally of the trough, and stop devices adjacent said section to engage the matches and prevent their retrograde movement during the return strokes of the bottom section.

8. In mechanism of the character described, a trough provided in its bottom 40 with discharge openings in spaced relation to each other, and vibratory feed devices located in such bottom in the space between said openings, said devices being movable longitudinally and independently of the body of the trough.

9. In mechanism of the character described, a trough provided in its bottom with discharge openings in spaced relation to each other, means for feeding matches along the 50 trough to said openings, a vibrating feeding section located in such bottom in the space between said openings, said section being movable longitudinally and independently of the body of the trough, and a jarring member adjacent said latter section and movable longitudinally and independently thereof.

10. In mechanism of the character described, a trough provided with discharge 60 openings in spaced relation to each other, means for feeding matches along the trough to said openings, and match-jarring means adjacent said openings, said jarring means being operative longitudinally and inde-

pendently of the trough and also independently of the said feeding means.

11. In mechanism of the character described, a trough provided with discharge openings in spaced relation to each other, means for feeding matches along the trough 70 to the said openings, a vibrating bottom section between said openings having transverse rack teeth arranged to engage the matches and progressively feed them, and stop devices adjacent said section to engage 75 the matches and prevent their retrograde movement, the strokes of said stop devices being less in range than those of the bottom section.

12. In mechanism of the character described, a trough provided with discharge openings in spaced relation to each other, a vibrating feed section having transverse rack teeth arranged to engage the matches and progressively feed them, an independently vibrating section having corresponding teeth, and means for vibrating said latter section within a shorter range than the former section.

13. In mechanism of the character described, the combination with a feed-trough, of a match-racking bar overhanging the same longitudinally thereof, a series of overlapping spring-pawl members connected with said bar and depending successively 95 therefrom, a spring pressure member secured to said bar and extending horizontally forward of said pawl members, and means for longitudinally reciprocating said bar and its attached spring members.

14. In mechanism of the character described, the combination with a feed-trough, of a match-racking bar overhanging the same longitudinally thereof, a series of overlapping spring-pawl members connected 105 with said bar and depending successively therefrom, a spring pressure member secured to said bar and extending horizontally forward of said pawl members, means for longitudinally reciprocating said bar and its 110 attached spring members, and means for raising said bar and members during their return or inactive stroke and for permitting their descent during their succeeding stroke.

15. In mechanism of the character described, the combination with a trough provided with discharge openings, of reciprocal gates for the respective openings, a reciprocal supporting member for one of said gates, a spring-controlled sliding connection between said latter gate and its supporting member, a supporting member for the other gate, and a rigid connection between said latter supporting member and the said spring-controlled connection.

16. In mechanism of the character described, the combination with a trough provided with discharge openings, of oppo-

sitely-movable cut-off gates for each of said openings, connections between the corresponding gates of the respective openings, means for positively retracting the said gates from the openings and means, including spring connections, for returning said gates to close the openings.

17. In mechanism of the character described, a match-feeding trough arranged alongside of the discharge end of a match machine, and into which the matches are discharged directly from the match machine, a portion of the side wall of said trough ad-

jacent the match machine being open, means for adjustably supporting the trough adjacent the match machine, and a relatively-stationary wall between the open side portion of the trough and the match machine. 15

Signed at Barberton, in the county of Summit, and State of Ohio, this 23rd day of April, A. D. 1914. 20
